ELECTRIC CLOCK

Max Schlenker, Peru, Ill., assignor to General Time Instruments Corporation, New York, N. Y., a corporation of Delaware

Application July 23, 1938, Serial No. 220,872

2 Claims. (Cl. 200—67)

This invention relates to improvements in electric clocks, and in particular to clocks wherein a spring is the principal source of power for driving the clock train and electro-magnetic means are provided for intermittently tensioning the spring.

This type of clock is widely used in automobiles which use, due to the vibration and the dust and dirt accompanying such use, imposes severe conditions of operation upon the clock and in particular upon the contacts for said electromagnetic means. One difficulty in the construction of the contacts is that if they come together with sufficient impact to make a good contact there will be a rebound which immediately destroys the contact and causes arcing, whereas if they are brought together slowly to avoid the rebound there is not likely to be sufficient force to effect a low resistance contact. This difficulty may be overcome by mounting one of the contacts upon a resilient member which will absorb the impact and prevent rebound.

I have found that the above mentioned resilient mounting in combination with certain means herein described to effect a rapid and forcible make and break will produce a very satisfactory contact mechanism, that will not arc, and one that is especially well suited for use in electric clocks. I have further found that an electric clock embodying said contact mechanism and certain other novel features herein described will operate accurately throughout a long life in the presence of such adverse conditions as may be encountered in automobile use, and is of sturdy, compact and inexpensive construction.

An object of my invention is to provide an improved electric clock wherein the power for the operation is supplied intermittently by electro-magnetic means.

A further object is to provide a clock in which the contacts are closed forcibly and in which a wiping action ensues if an electrical contact is not effected simultaneously with mechanical contact.

A further object is to provide, for an electric clock, mechanism whereby electric contact can be made without arcing and wherein rebound of the contacts is eliminated.

A further object is to provide a clock in which the contacts are mounted on movable members providing relative motion between the two contacts, such that the break is effected at a different point than the make so that any corrosion due to arcing will not impede the facility with which the circuit is made.

A further object is to provide a clock in which means are provided for driving the clockwork while the main driving spring is being tensioned.

A further object is to provide an improved electrical clock of simple and inexpensive construction and of positive and accurate operation.

Other objects, features and advantages will become apparent as this description proceeds.

Reference is hereby made to the accompanying figures which illustrate a preferred embodiment of my invention and in which like reference numerals refer to like parts.

Figure 1 is an elevation of an electrical clock a portion of the contact mechanism being omitted for the sake of clarity;

Figure 2 is a section taken along line 2—2 of Figure 1;

Figure 3 is a section taken along lines 3—3 of Figure 1;

Figure 4 is a detailed view of the contacts;

Figure 5 is a side elevation of the contacts shown in Figure 4; and

Figure 6 is a detail sectional view of the center shafts and the gears, ratchets and contact lever mounted thereon.

Reference numerals 10 to 13 refer to suitable frame plates, the plates 10 and 11 supporting the usual clockwork which is not shown herein and the plates 12 and 13 supporting the electromagnetic driving means for the clockwork, the plates being affixed to and spaced from each other by suitable spacing members only one of which, spacing member 14, is herein shown. A gear 15 and an associated collar 16 are loosely mounted on shaft 17, the shaft being journaled in plate 10 and in bearing 63 affixed to plate 12. The gear 15 and collar 16 normally rotate with shaft 17, the friction spider 61 forcing collar 16 against the shoulder of the enlarged portion 62 of shaft 17.

This friction is provided to permit setting of the clock hands. Gear 15 is adapted to mesh with and drive the clockwork. A ratchet 18 is loosely mounted on shaft 17 to rotate independently thereof, and a spring 19 is connected at either end to ratchet 18 and to gear 15 so that the gear and shaft may be driven by the rotation of the ratchet when the spring is tensioned. The plate 11 is apertured to permit collar 16 and spring 19 to pass therethrough.

A shaft 20 is journaled in plate 13 and in bearing 63 in plate 12 and is concentric with ratchet 18 loosely mounted on shaft 17 on the opposite side of plate 12; taken together, shafts 17 and 20 can be considered as a single split shaft. Magnets 21 and 22 are suitably mounted on plate

13 and an armature 23 is provided to co-operate with the magnets, the armature being affixed to shaft 20. A pin 24 projects from armature 23 to which pin is adapted to be affixed one end of spring 26, the other end of the spring being affixed to a suitable pin 25 which projects from the plate 12. Arms 27 and 28 carrying pawls 29 and 30 are mounted on armature 23 and project through slots 31 and 32 in plate 12 so that the pawls may engage ratchet 18 and rotate the same when the armature is rotated in the clockwise direction as shown in Figure 2. A fixed pawl 33 is provided to prevent counterclockwise rotation of the ratchet 18 when the armature 23 is rotated in a counterclockwise direction.

It will be noted that as the armature 23 is rotated by spring 26, the resulting rotation of the ratchet wheel will drive the clockwork through gear 15 and driving spring 19. Just before the armature has reached the limit of its rotation, which is defined by the engagement of the armature with spacing member 14, certain contacts are closed energizing the electromagnet and attracting the armature in a counterclockwise direction to tension the spring. During this period there is no force tending to rotate the ratchet in the clockwise direction but the spring 19 will continue to drive the clockwork for a short period of time, thus providing a continuous driving force for the clockwork.

An arm 36 is affixed to shaft 20 to which arm is attached resilient member 37 carrying at one end contact 38.

It will be noted that arm 36 extends out from the shaft in a direction generally opposite to the direction in which the resilient member extends from the arm, the intermediate portion of the arm being positioned close to shaft 20. This permits the use of a longer resilient member which is found to give superior results in preventing rebound of the contact than if one end of the resilient member were affixed directly to shaft 20.

Frame plates 39 and 40 are suitably affixed to the frame plate 13 and insulated therefrom by an insulating member 41, the plates being suitably spaced from one another by members 42. A shaft 43 is journaled in plates 39 and 40 to which shaft is affixed a pivoted member 44 having an insulating arm 45 projecting therefrom and a second arm which carries a co-operating contact 47 and a projection 48. One end of overcenter spring 50 is affixed to projection 48, the other end being attached to a pin 49 suitably mounted on plate 39. The positioning of the spring is such that as the pivoted member is rotated the spring will pass over the center of shaft 43 and tend to continue the rotation of the pivoted member to an extreme position. In other words the overcenter spring acts as a positioning member which may be tripped through an intermediate position to cause the pivoted member to assume one of two extreme positions. A pigtail connector 51, in the form of a hair spring is provided which is affixed to shaft 43, the other end of the pigtail being anchored to the plate 40 at 52, to provide a low resistance electrical connection between contact 47 and plate 40.

Terminal posts 55 and 56 are provided on plate 13, terminal 55, magnet 21, conductor 57, magnet 22, conductor 58, plate 40 and contact 47 being in series with each other, and terminal 56 being grounded. Contact 38 is also grounded so that the making of contacts 38 and 47 will ener-

gize the magnets and attract armature 23 from the position shown in Figure 2 to a position overlying the poles of the magnets, thereby tensioning the spring 26. Upon energization of the magnets, arm 36, resilient member 37 and contact 38 are rotated from the position shown in Figure 3, causing rotation of pivoted member 44 in a clockwise direction through an intermediate position wherein overcenter spring 50 passes over the center of pivot 43 so that further rotation of the pivoted member is caused by said spring, thereby breaking the contact and bringing the pivoted member into engagement with a suitable stop, or bringing the insulating arm 45 into engagement with contact 38. It will be noted in Figure 3 that the contact is first effected at a point near the outer end of contact 47, and as the two contacts are rotated about their respective centers, the point of contact moves inwardly along contact 47 and around the convex surface of contact 38, so that the break is effected between different points of the contacts than the make which results in a wiping action which keeps the contacts clean. Consequently, any corrosion of the contacts due to arcing will be confined to portions of the contact surfaces that are not in contact with each other until after the circuit has been well established through other portions of the contact surfaces.

Immediately after the break, the rotation of arm 36 reverses due to the action of the spring 26 on armature 23, magnets 21 and 22 having been de-energized, and the pivoted member 44 is rotated in a counterclockwise direction, in opposition to overcenter spring 50, by contact 38 which is in engagement with insulating arm 45. The rate of rotation is controlled by the escapement of the clockwork which is driven through ratchet 18 and gear 15 by rotating armature 23 as above described. As the pivoted member is rotated from the position shown in Figure 4 through an intermediate position wherein spring 50 passes over the center of pivot 43, the contact 47 is snapped into engagement with contact 38 as shown in Figure 3, thereby establishing the circuit through the magnets 21 and 22 for tensioning spring 26. If, however, the circuit is not established immediately due to the presence of dust or dirt on the contacts, further rotation of the contacts beyond the position shown in Figure 3 produces a wiping action which will tend to clean the contacts and permit establishment of the circuit before the contact 38 comes into contact with stop 60, projecting from plate 39. Contact with the stop will provide an additional opportunity for establishment of the circuit, should the usual contacting means fail.

If the battery or other source of power be disconnected for a sufficient period, contact 38 will be forced against stop 60 by the tension of spring 26 and by the tension of spring 50 acting through contact 47, thereby ensuring a good contact immediately upon the connection of the battery into the circuit.

It will be noted that with the construction herein disclosed the relative motions between the two contacts results in a wiping action which keeps the surfaces clean and that the break occurs at a different point than the make. Furthermore, the resilient mounting of the actuating contact 38 tends to absorb any shock tending to cause a rebound between the contacts. The overcenter spring and the pigtail connector also serve as a resilient mounting for the other con-

tact and may co-operate with resilient member 37 to prevent rebound and consequent arcing.

The stop 60 provides an additional point of contact enabling the clock to be started immediately after a period of non-use during which the contacts often become dirty. The stop also prevents excess wear of the resiliently mounted contacts due to vibration of the automobile during a period of non-use, that is, when the battery is disconnected from the circuit.

Although I have herein shown and described a preferred embodiment of my invention, it is understood that certain modifications thereof and changes in the shape and size of the parts thereof may be effected without departing from the spirit of my invention as defined in the following claims.

I claim:

1. Contact mechanism comprising a frame, a pivoted member carrying a first contact and an insulating projection, a second contact mounted for oscillating motion and adapted to engage said insulating projection to rotate said pivoted

member in one direction, and adapted to engage said first contact to rotate said pivoted member in the other direction, resilient positioning means mounted between said pivoted member and said frame to snap said pivoted member from an intermediate position to either of two extreme positions, and a projection from said frame against which said second contact is urged by said first contact through influence of said resilient positioning means to define one of said extreme positions.

5 2. Contact mechanism comprising a frame, a rotatable shaft, an arm rigidly affixed to said shaft, a resilient member affixed to and extending from said arm back toward said shaft and beyond said shaft, an actuating contact carried by said resilient member at its free end, an actuated contact for co-operation therewith pivotally mounted with respect to said frame, and overcenter resilient means for rotating said actuated contact into and out of engagement with said actuating contact.

15 MAX SCHLENKER.
